BUTTON FORMING AND WIRE INSERTING
MACHINE

Louis C. Stringer, Chicago, Ill., assignor to Electronics Supply Corp., a corporation of Delaware

Application May 6, 1937, Serial No. 141,149

8 Claims. (Cl. 176—3)

The present invention relates to what is believed to be a new and structurally novel hand actuated and controlled machine for use in the electric lamp and bulb industry, wherein said machine is expressly constructed to operate substantially automatically and mechanically to expeditiously construct a so-called button and wire assembly.

In this particular line of endeavor much precision and care, requiring painstaking efforts, must be resorted to in perfectly constructing the filament mount preparatory to enveloping or incorporating it in the bulb or globe. In the more expensive type bulbs a now somewhat primitive method is followed which consists in making that portion of the mount known as the multiple wire retention button. It is unnecessary, it is believed, to provide here a resume of this class of handiwork other than to say that after the head or button is fashioned, the filament supporting wires are attached thereto, by hand, involving a one-by-one tedious and unreliable procedure.

Confronted with the unnecessary time consuming and laborious hand methods now in use, I have, after much experimentation and due deliberation, developed a machine which will do mechanically, which was heretofore done by hand, such machine being so designed as to do a better job in an almost uncanny uniform and standardized manner.

While the cardinal point of the conception is the preferred machinery adapted for this express purpose, novelty is thought to reside also in the methodical or procedural ways and means of casting the button, imbedding the wires, and clenching or bending the wires into requisite exactitude in so far as companionate relationship is concerned.

Manifestly, my chief aim is, therefore, to promote progress in this industrial line of endeavor through the adoption and use of an expedient and practicable mechanical machine or device, which, through the aid of a skilled attendant, will permit the button and wire assembly, as a unit, to be perfected with requisite certainty and speed.

Other features and advantages of the invention will become more readily apparent from the following description and drawings.

50 In the drawings:

Figure 1 is an elevational view showing a portion of a bench with the complete machine supported thereon, with the parts of the machine in readiness to subject the glass stem or rod to the primary step of heating and melting.

Figure 2 is a horizontal section on the plane of the line 2—2 of Figure 1.

Figure 3 is a vertical sectional view taken on the plane of the line 3—3 of Figure 1.

Figure 4 is a bottom plan view of the wire holding and inserting oscillatory chuck.

Figure 5 is a horizontal sectional view which may be said to be approximately on the plane of the line 5—5 of Figure 3.

Figure 6 is a diagrammatic plan view of the 10 radially projectible and retractible wire holding plungers or ejectors.

Figure 7 is a horizontal section on the plane of the line 7—7 of Figure 1.

Figure 8 is a view partly in section and partly 15 in elevation showing features of the so-called mount, that is, the standard or reed and glass button.

Figure 9 is a horizontal section on the line 9—9 of Figure 8.

Figure 10 is a perspective view of one of the 20 wire adapting and projecting plungers.

Figure 11 is a view in section and elevation showing how the wire bending result is accomplished.

Figure 12 is a perspective group assembly view 25 of the features which go to make up that part of the mount referred to in the trade as the multiple wire-equipped button.

Figure 13 is a section on the line 13—13 of 30 Figure 11.

Figure 14 is a detail sectional view showing how the two companion parts of the casting mold come together to fashion or form the head of the button.

Figure 15 is a fragmentary perspective view of 35 the upper end of the fluted or grooved movable mold section.

Referring now to the drawings, and conveniently to Figure 1, it will be observed that the invention is a bench-type contrivance such as may be conveniently referred to as a machine. The bench is indicated by the numeral 16. The stand or base unit is unitarily identified by the numeral 17 and comprises an appropriate base plate 18 having perpendicular uprights 19 with swivel fixtures 20 supported on the upper ends thereof. The burner heads, of the gas blower type, and denoted by the numerals 21, are supported in these fixtures so as to permit the emanating flames to be properly regulated with respect to the work being acted on. Each burner head includes a manifold 22 with a battery of nozzles 23. Rising centrally between the uprights 19 is an integral adapter member 24 having a 50

vertical slot 25 provided along one edge with selectively usable keeper notches 26. This constitutes the bearing or mounting for the molding and bending unit. Also forming a part of the base is a suitable inclosure or housing 27 forming a casing for the pinion 28. As seen in Figure 7, the gear casing has a bearing 29 to accommodate the pinion shaft 30 and hand-wheel 31. It will also be observed in Figure 7 that there is a slot in the adapter mounting 24 opposite to the slot 25 permitting entrance of the pinion. Then, too, the base includes a standard 32 rising to an appropriate height and having a horizontal reach arm 33 at its top adjustably mounted as at 34. On the free end of the reach arm is a depending pin 35 terminating in a head 36 suitably faced with a graphite or carbon disk 37. The features 36 and 37 constitute the relatively stationary part of the casting mold.

Advantage is taken of this arrangement by placing on the pin a sleeve 38 having bayonet slot and pin means 39 and 40. At the bottom of the sleeve is a knurled collar 41 which functions as a wire bending matrix, as hereinafter disclosed (see Figure 11).

I next call attention to the numeral 42 which designates a magazine-type chuck. This is adapted to be charged with the customary long and short filament supporting wires 43 and 44, respectively. Structurally, this part 42 comprises a disk or plate 45 centrally apertured and having a series of properly spaced radial grooves 46 constituting slideways for the projectible and retractable plungers 47. The plungers are made in long and short series, as shown diagrammatically in Figure 6, to accommodate correspondingly proportioned wires 43 and 44. Then, too, each plunger has at its outer end a head 48 provided with a seat 49 to receive the corresponding end of the wire to be inserted in the button. Furthermore, the numeral 50 designates an actuating pin extending down through adjacent slots in the plate, as seen in Figures 3 and 11. The marginal portion of the wire charged plate 45 is surrounded by an annular rim including a relatively rotatable ring 51 having riveted thereto a flanged annulus 52. These two features 51 and 52 provide the turnable or rotatable rim, this being provided with an operating handle 53. The part 51 has cam slots 54 therein, as seen in Figure 4, to accommodate the headed end of the pin 50. Hence, by rotating the rim in relation to the plate 45, the cam slots and coacting pins coordinate to project the plungers 47 inwardly and to carry the wires in the same direction for anchorage.

It is to be observed that the central portion of the plate 45 is provided with a square collar 55 fitting non-rotatably on the correspondingly shaped upper end of a reciprocating cylinder 56 slidably mounted in the adapter mounting 24. Furthermore, the upper part 57 of this collar constitutes the relatively movable matrix to contact with the aforementioned relatively stationary matrix 41 to bend the wires 43 and 44.

Attention is now called to the numeral 58, this designating a reciprocating tube. The upper end thereof is formed into a head, as at 59 (see Figures 14 and 15), this head forming a relatively movable button casting mold section. The numeral 60 designates a graphite cup located in the head, which features are formed with registering slots, that is, a plurality of radial slots 61, to properly space the inner ends of the wires 43 and 44 as they are projected, by the afore-

said plungers 47, into the molten glass button. As seen in Figure 3, this tube or inner cylinder is slidably mounted by an appropriate spacer 62 in the outer cylinder 56. Moreover, it is provided with a lifting and lowering handle 63 extending out through the slots 25 and selectively engageable with the keeper notches 26.

In order to simplify the assembly, there is slidably mounted in the inner cylinder or tube 58 the hand twirled holding and spinning spindle 64 for the glass rod 65. As before indicated, this glass rod is commonly referred to in the trade as a button. It is slipped down into a socket in the upper end of the spindle 64 and is held therein by spring retention clips 65', as shown in Figure 8. It is alternately rotatable and slidable in the inner cylinder 58 and provided at its bottom with an operating knob 66. As soon in Figure 3, the lower knob-equipped portion of the spindle is properly shouldered as indicated at 67 to limit the downward drop of said spindle when it is released by hand.

In practice it is to be understood that the chuck-type wire holding magazine 42 is properly charged with the customary group of seven wires, this being done by a companion attendant so that it is in readiness for use by the operator of the machine. It follows, therefore, that when the magazine 42 has been properly loaded with the wires, it is placed on top of the reciprocating cylinder or jack 56.

The operation of the machine is as follows: The first thing to do is to place one of the standard cut reeds or glass rods 65 in the holding spindle 64. This is accomplished as seen in Figure 8 and the machine is now set to begin operations. In the first place, the operator catches hold of the knob 66 and pushes the spindle 64 upwardly in relation to the relatively stationary surrounding sleeve or tube 58. This projects the upper end of the glass rod 65 to a point above the chuck and within the focal plane of the nozzles 23. The nozzles can be properly adjusted in relation to the work to properly play or impinge thereon. Moreover, the burner control means is within convenient reach of the operator (not shown) whereby to properly time the heating of the glass rod 65.

Secondly, after the glass rod 65 has been heated to the desired degree, the knob 66 is released and the holder 64 dropped down to the position seen in Figure 3. While the glass is in this molten or substantially plastic state, the next operation is to grasp the handle 63, lift up on the tube or sleeve 58 to bring the two heads 36 and 59 together to mash or compress the glass therebetween. This casts or forms the head 68 on the glass rod. Then the handle 63 is properly lowered to bring the headed glass rod down into the chuck again so that the inner ends of the wires 43 and 44 can be projected into the glass head or button 68. This means that all that is necessary here is to grasp the handle 53 of the chuck and to turn it, thus projecting the wires through the slits 61 into the glass to properly space and anchor the wires. When this is accomplished, the handle 63 is returned to its original position so that the wires register again with the slots 46 in the chuck plate 45.

After the wires have been allowed to set sufficiently long to become satisfactorily anchored in the button, they must then be bent into the perpendicular L-shaped form seen in Figure 11.

This is accomplished by lifting the complete jack, including the chuck head, to bring the

matrices 41 and 57 into play. Before this is effected, however, the sleeve 38 of the matrix 41 is lowered and locked in place so that the cup end 41 is now down over the molding head 36, as shown in Figure 11. The matrix 41 thus becomes a form around which the wires are bent to L-shape form. As the movable matrix 57 comes up and around the matrix 41, this brings the parts into telescoping relationship, and obviously bends the wires. Now the jack, including the chuck or magazine, is lowered, and the wire-equipped unit is extracted, as is obvious.

It has been found expedient and practicable to include in the upper end of the cylinder an insert 69 having a cushioning spring to allow the head 59 to recede into the same during the wire bending operation, as is brought out in Figure 11.

The method phase of the discovery is evident from the diagrammatic group illustration appearing in Figure 12 of the drawings. First, we begin with the glass rod 65, which is a stock product. This is inserted in the hand spindle which is lifted up and turned back and forth with the fingers while the flames from the burners 25 impinge thereon. This oscillation about the axis of the rod quickly preheats the upper end of the glass to a state to permit it to be flattened into the button 68 this being accomplished by squeezing or clamping the heated end of the glass rod 30 between the clamping or molding heads 59 and 36, respectively (see Figure 14). Then the wires are inserted in the manner described and as shown in said Figure 12. Finally, they are bent mechanically by the liftable jack means. These 35 steps are brought out to advantage in Figure 12 of the drawings.

It is evident that a machine of the type herein shown and described is calculated to fulfill a long felt need in this particular line of endeavor. It is 40 characterized by relative simplicity, taking into consideration the progressive steps to be carried into effect. Its operation is sufficiently simple to justify unqualified endorsement by the trade in general.

45 It is thought that the description taken in connection with the drawings will enable a clear understanding of the invention to be had. Therefore, a more lengthy description is thought unnecessary.

50 While the preferred embodiment of the invention has been shown and described, it is to be understood that minor changes coming within the field of invention claimed may be resorted to if desired.

55 I claim:

1. A method of casting and constructing a button and wire assembly for use in an incandescent bulb mount consisting in first holding one end of the conventional glass rod in the path of a source 60 of melting heat; secondly, compressing the melted end of the rod between approachable and separable mold units; third, mechanically inserting a multiplicity of filament supporting wires in the peripheral portion of the button; and, finally, 65 simultaneously subjecting the anchored wire ends to the clenching action of a press to bend the wires into relative parallel filament supporting relationship.

2. In an electric lamp button fashioning and 70 wire inserting and assembling machine of the class described, a relatively stationary support, heating means on said support, and a multi-part device on said support cooperable with the heating means, said device being manually actuated 75 and controlled and having means therein for

spinning the conventional glass rod in the presence of heat, compressing the heated end to form the button, automatically and simultaneously anchoring filament supporting wires in the button while in a molten state, and additional progressively actuatable means for thereafter bending the anchored ends of the wires to dispose them in substantial parallelism for reception of the filament.

3. In a button forming and wire inserting and 10 bending machine of the class described, means for supporting and handling a perpendicularly disposed glass rod, adjustable means for fusing one end portion of said rod, mechanical means for applying pressure to and compressing the 15 fused end of said rod to form the button thereon, means coacting with the aforesaid parts for simultaneously feeding a plurality of wires radially into position so that their inner ends become imbedded in said button, and telescopically cooperable means for bending and shaping the inner ends of the wires to dispose said wires in circumferentially spaced parallel order and in longitudinal alignment to the axis of said glass rod. 20

4. In a button-forming, wire-inserting and 25 bending machine of the class described, a base, opposed sets of burners adjustably supported on said base, a vertical standard attached to and rising from said base, a reach arm on the upper end of said standard overlying the base, a pin 30 attached to and depending from said arm, a sleeve slidably mounted on said pin and including a portion forming a wire-bending matrix, a cylinder slidably mounted on said base beneath said pin and sleeve, said pin having a glass compressing head, a second sleeve mounted for reciprocation in said cylinder, a handle for lifting and lowering said second named sleeve, said last named sleeve being located directly beneath said first sleeve and pin and having a head on its upper end cooperable with said first named head, means for raising and lowering the cylinder and sleeve as a unit in relation to said base, and a multiple wire charged magazine removably supported on said cylinder and including a wire 35 bending matrix opposed to said first named matrix. 40

5. In a button-forming, wire-inserting and bending machine of the class described, a base,

opposed sets of burners, adjustably supported on said base, a vertical standard attached to and rising from said base, a reach arm on the upper end of said standard overlying the base, a pin attached to and depending from said arm, a sleeve slidably mounted on said pin and including a portion forming a wire-bending matrix, a cylinder slidably mounted on said base beneath said pin and sleeve, said pin having a glass compressing head, a second sleeve mounted for reciprocation in said cylinder, a handle for lifting and lowering said second named sleeve, said last named sleeve being located directly beneath said pin and having a head on its upper end cooperable with said first named head, means for raising and lowering the cylinder and sleeve as a unit in relation to said base, and a wire charged magazine removably supported on said cylinder and including a wire bending matrix opposed to said first named matrix, and a hand twirled glass holding spindle slidably and 50 rotatably mounted in the second named sleeve 55 and operable independently in relation thereto. 60

6. A method of casting and constructing a button and wire assembly for use in an incandescent bulb mount consisting in first holding one 70

end of the conventional glass rod in the path of a source of melting heat while oscillating about the axis of said rod; secondly, compressing the melted end of the rod between coacting mold units; third, mechanically inserting a multiplicity of filament supporting wires in peripheral portion of the thus melted and compressed button; and finally, simultaneously subjecting the anchored wire-ends to the clenching action of a 10 press to bend the wires into relative parallel filament supporting relationship.

7. A method of casting and constructing a button and wire assembly for use in an incandescent bulb mount consisting in first momentarily and movably holding one end of the conventional glass rod in the path of a relatively fixed source of melting heat of predetermined intensity while simultaneously rotating the rod in relation to the heat zone; secondly, compressing the melted end of the rod between button forming mold units; third, mechanically inserting from a pre-charged magazine, a plu- 15

rality of bendable filament supporting wires in the peripheral portion of the button; and finally, simultaneously subjecting the anchored ends to a bending operation.

8. In a construction of the class described, a base, a plurality of burners supported on said base, a standard attached to and rising from said base in predetermined relationship with respect to the burners, an arm on the upper end of said standard, a pin attached to and depending from said arm, a cylinder slidably mounted on the base and located between the arm and said base, said pin having a compressing head, a sleeve slidable in said cylinder, a handle for lifting and lowering said sleeve, said sleeve being located directly beneath said pin and having a head on its upper end cooperable with said first named head, means for raising and lowering the cylinder supported from said base, and a multiple wire charged magazine supported on said cylinder. 10 15 20

LOUIS C. STRINGER.
